DESIGN FOR A PANEL MAT

William J. Adams, Jr., Hartsdale, N. Y., assignor
to Bell Telephone Laboratories, Incorporated,
New York, N. Y., a corporation of New York

Application December 28, 1934, Serial No. 54,629

Term of patent 14 years

To all whom it may concern:

Be it known that I, William J. Adams, Jr., a citizen of the United States of America, residing at Hartsdale, in the county of Westchester and State of New York, have invented a new, original, and ornamental Design for a Panel Mat, of which the following is a specification, reference being had to the accompanying drawing, forming a part thereof.

Fig. 1 of the drawing is a front face plan view of the panel mat and showing my new design;

Fig. 2 is a front face plan view of either a right or left upper portion of the panel mat shown in Fig. 1 and drawn to an enlarged scale relative to Fig. 1;

Fig. 3 is a view in cross-section of an upper portion of the panel mat shown in Fig. 1 enlarged relative to Fig. 1 and taken on the lines 3—3 and viewed in the direction indicated by the arrows; and

Fig. 4 is a view in cross-section of the panel mat taken on the lines 4—4 in Fig. 2 and viewed in the direction indicated by the arrows. Fig. 4 is drawn to the same scale as Fig. 2.

I claim:

The ornamental design for a panel mat as shown.

In witness whereof, I hereunto subscribe my name this 26th day of December, 1934.

WILLIAM J. ADAMS, JR.
